COMPRESSOR HEAD AND GOVERNOR
ASSEMBLYEllis E. Hewitt, Edgewood, Pa., assignor to The
Westinghouse Air Brake Company, Wilmerding,
Pa., a corporation of Pennsylvania

Application April 30, 1943, Serial No. 485,192

4 Claims. (Cl. 230—9)

This invention relates to steam driven air compressors, and particularly to a fluid pressure actuated governor for controlling operation of a compressor of the type employed in railway service.

The well known steam driven compressor always carried on a locomotive in steam road service, and functioning to supply compressed air to the main reservoirs for use in the air brake system, is controlled automatically by means of a fluid pressure actuated governor, which is customarily interposed in the steam supply pipe leading to the operating cylinders of the compressor. The governor in its standard form consists of a steam valve having an operating piston, and a pair of independently operative pilot valve mechanism commonly called low pressure and high pressure tops, which control the supply of compressed air to the operating piston in accordance with the demand for main reservoir air under different service conditions. The casting structure of this type of compressor governor, which is usually installed in a position some distance from the compressor itself, includes a relatively bulky steam valve section requiring an individual mounting bracket for holding the governor device rigidly in place on the locomotive, and necessitates the employment of two steam pipe connections, which must be accurately made and maintained to prevent leakage. Such a governor is generally lubricated through the medium of copper tubing which is adapted to conduct oil from a lubricator mechanism operated by the compressor.

A compressor of the class referred to, such as the well known cross compound steam driven air compressor, carries a double cylinder head containing a steam operated piston valve and a mechanically actuated reversing valve, both of which are usually lubricated by separate oil conducting copper tubes fed from the automatic lubricator mechanism. Efficient lubrication of the compressor valves, and of the governor just described, would be promoted by a construction and arrangement of the parts making possible the lubrication of all these elements from a single point, but such a result is not practicable with the compressor head and separately mounted governor heretofore employed.

It is an object of my invention to provide an improved steam driven compressor equipment including a compressor having a cylinder head similar to that described, but carrying a compressor governor mechanism of novel construc-

tion, which forms an integral part of the cylinder head.

Another object of the invention is to provide a combination cylinder head and governor for a steam driven compressor, which are constructed and arranged to provide a steam inlet into which lubricant can be introduced in the form of spray, thereby adequately lubricating all the associated operating elements from a single point.

A further object of the invention is to provide an improved compressor head having a steam supply controlling valve portion formed integrally therein, and a compressor governor constructed and arranged to be mounted on said valve portion without altering the normal clearance dimensions of the compressor apparatus as a whole.

Still another object of the invention is to provide an improved head and governor assembly for a steam driven compressor, in which head is formed a steam intake chamber containing a valve seat, lubricant atomizing means for introducing oil in the form of mist into the steam intake chamber, and a governor portion mounted on the compressor head and having a valve engageable with the valve seat for controlling admission of both steam and lubricant to the governor and other operating elements contained in the head.

Other objects and advantages of the invention will appear in the following more detailed description thereof, taken in connection with the accompanying drawings, in which

Fig. 1 is an elevational view of cross compound compressor having a combination cylinder head and governor assembly constructed in accordance with the invention;

Fig. 2 is a fragmentary plan view of the head and assembly shown in Fig. 1;

Fig. 3 is an enlarged detail view of the governor portion of the assembly, with certain parts thereof shown in section;

Fig. 4 is a fragmentary sectional view taken substantially along the line 4—4 of Fig. 3, and

Fig. 5 is a schematic view representing the compressor in association with a main reservoir and the brake valve of an air brake system.

As shown in Fig. 1 of the drawings, the cross compound air compressor comprises integrally formed low and high pressure air compressing cylinders 10 and 11, a centerpiece or casting 12 secured to the cylinder casting by means of bolts 13, a lagging casing enclosing integrally cast high and low pressure steam cylinders, the latter being indicated by the number 14, which are located

directly above the respective air cylinders 10 and 11 and are bolted to the centerpiece 12, and a double cylinder head 15 which is mounted on the integrally formed steam cylinders and secured in place by bolts 16. The details of construction and the operation of a cross compound air compressor are well known and need not be described here, but it will be understood that live steam admitted by way of a steam inlet 17 is conducted through an inlet passage 18 formed in the wall of cylinder 14 and through other communications controlled by the compressor governor 20, presently to be described, to the usual reversing valve and steam distribution controlling valve assembled within the head 15, which cooperate to direct the steam into the cylinders for reciprocating the pistons of the compressor.

The compressor illustrated in Fig. 1 is equipped with automatic lubricator means comprising a force feed lubricator mechanism 25, which is mounted on the second stage or high pressure air cylinder 11, and which is operative with the compressor to supply lubricant under pressure through a conduit 26 to an atomizer device 27 mounted on the cylinder head 15, as hereinafter more fully described. The lubricator mechanism 25 is not illustrated in detail in Fig. 1, but preferably has a construction such as that of the apparatus disclosed and claimed in my copending application Serial No. 492,794, filed June 30, 1942, in the United States Patent Office.

It will be noted that the portion of the double cylinder head 15 located directly above the cylinder 14, which is the high pressure steam cylinder of the compressor, has formed thereon an elevated valve housing portion 30 which is adapted to contain the reversing valve mechanism always provided in this class of apparatus but not illustrated in the drawings. As is best shown in Figs. 1 and 4 of the drawings, the end of the compressor head 15 disposed outwardly of the valve housing portion 30 just mentioned, and thus located above the steam inlet passageway 18 formed in the cylinder 14, carries an integral hollow ledge or bracket portion designated generally by the reference character 32, which ledge portion constitutes a portion of the improved compressor governor device 20 already mentioned and which serves to support the other portions of the device. According to the invention, the hollow ledge portion 32 of the compressor head 15 has formed therein a steam outlet passageway 34, which is adapted to communicate by way of other interior cavities, formed in the head and not illustrated, with the usual reversing valve assembly and piston valve assembly controlling the flow of steam to the compressor pistons. Also formed within the ledge portion 32 of the compressor head 15 is steam inlet or atomizing chamber 35, which is separated from the steam outlet passageway 34 by a partition 36 and which communicates with the steam inlet passageway 18. A valve seat bushing 39 having an aperture 40 is mounted in screw-threaded relation with the partition 36 for defining a communication between the chamber 35 and the passageway 34. The upper end of the aperture flares upwardly and outwardly to form a valve seat 41.

The casing structure of the governor mechanism 20 includes a casing section 42, which is mounted on a suitable annular mounting face 43 formed on the ledge portion 32 of the compressor head, and a body section 45 which is

mounted on the upper portion of the casing section 42. The casing sections may be secured in place by suitable fastenings, such as bolts, not shown.

The casing section 42 has a lower portion 48 and an upper portion 49 which are joined by means of a plurality of spaced vertical portions 50, as best shown in Fig. 4 of the drawings. Mounted within the upper portion 49 is a cylindrical bushing 52 which rests on the upper end of a dish-shaped casing element 53 having its lower portion mounted in engagement with the portion 48. The portion 48 has formed therein a central chamber 55 which is open to the atmosphere and contains a vertically arranged guide member 56 having a flange 57 clamped between the casing section 42 and the ledge portion 43 of the compressor head. Slidably mounted in a suitable bore formed in the guide member 56 is the stem of a steam valve element 58, which is disposed in the steam outlet passageway 34 and is adapted to engage the valve seat 41 of the bushing 39 carried in the compressor head. The stem of the valve member 58 is connected to a rod 60 extending downwardly from an operating piston 61 that is slidably mounted in the bushing 52. Formed at the upper side of the operating piston 61 is a chamber 63, which is contained in the body section 45 and is adapted to be supplied with compressed air, in a manner hereinafter explained, when the governor apparatus is conditioned for cutting off the flow of steam to the compressor. A restricted atmospheric vent, not shown in the drawings, is preferably provided for normally equalizing the pressure of fluid in the chamber 63 with that of the atmosphere.

Referring to Fig. 3, it will be observed that the chamber 63 extends upwardly into a portion 45a of the body section 45, which portion is formed integrally with the body section but is offset and inclined therefrom, so that with the body section mounted in place, all portions thereof are spaced from the elevated valve housing portion 30 of the compressor head 15, but are nevertheless contained substantially within an arc having the radius of the adjacent curved portion of the head. In other words, the body section 45 and portion 45a thereof are compacted and arranged to be carried on the compressor head within the clearance limits established by the structure of the compressor itself. The portion 45a of the governor body section is adapted to support a pair of pilot valve assemblies, designated generally as a low pressure top 65 and a high pressure top 66, which are similar in construction and extend outwardly and horizontally, as shown in Figs. 1, 2, and 3, but within the clearance dimensions of the compressor as just explained.

The valve assemblies contained in the low and high pressure tops 65 and 66 are designed for operation at different times to control operation of the compressor for maintaining a low fluid pressure in the receiving reservoir at one time and a high fluid pressure therein at another time. For example, when the compressor apparatus constitutes part of the equipment on a railway locomotive, as shown diagrammatically in Fig. 5, the low pressure top 65 may be arranged to control operation of the compressor in charging the reservoir 97 when the associated brake valve 98 is in brake releasing position, and the high pressure top 66 may be arranged to become operative to control the compressor while the

low pressure top is rendered inoperative upon movement of the brake valve to effect an application of the brakes. This particular operational characteristic of the governor assembly is well understood by those familiar with railway service, and thus need not be further explained.

For the purpose of the present disclosure, only the elements of the high pressure top 66 need be described, it being understood that the construction of the low pressure top 65 is substantially the same. The high pressure top comprises a cage element 70, mounted within a chamber 71 formed in the casing portion 45a, and projecting into the chamber 63, and an elongate cover 74 having screw-threaded connection with the portion 45a. Mounted in the cage member 70 is a valve element 75 which is engageable with a seat 76 for controlling communication from the chamber 71 to the chamber 63 in accordance with the movement of a flexible diaphragm 77 under the pressure of fluid admitted to the chamber 71 by way of a pipe 78 leading from the main reservoir. The valve element 75 is subject to the opposing forces exerted by a light spring 79, which urges the valve element away from its seat, and a metering spring 80, which acts inwardly against a follower member 81 and the flexible diaphragm 77, the metering spring being contained within the cover 74. The force exerted by the metering spring 80 may be varied in accordance with the adjustment of a set screw 83 mounted in the cover 74.

The valve assembly within the low pressure top 65 similarly controls communication through which compressed air may be admitted from a pipe 86 and chamber 87 to the chamber 63, in accordance with operating conditions as determined by operation of the air brakes, as hereinbefore explained.

Referring again to Fig. 4, the atomizing device 21, which is adapted to supply lubricant under pressure and in the form of mist into the path of steam flowing through chamber 35, comprises an elbow-shaped body 85, one portion of which is screwed into a suitably threaded opening in the compressor head 15, and the lower end of which is joined to the tube 26 through the medium of a sealing nipple 87 and clamping nut 88. Formed in the body 85 is a valve chamber 90 which communicates with the tube 26 and by way of a passage 91 with the atomizing chamber 35 in the compressor head, the passage 91 having a limited flow capacity as determined by the size of a restricted orifice 91a formed in a nozzle piece 92 secured to the body 85 within chamber 35. A valve element 93 is mounted within the valve chamber 90 and is normally urged into contact with a seat 94 under the force exerted by a spring 95, for controlling flow of lubricant from the pipe 26 to the valve chamber. The spring 95 is interposed between a follower member 97 engaging the valve element 93, and a shoulder formed on a plug member 98 screwed into the top of the body 85.

The various operating parts of the compressor governor assembly are shown in Figs. 3 and 4 in the positions assumed in rendering the compressor operative to supply compressed air to the receiving reservoirs. In order to understand operation of the apparatus, it may be assumed that the air brake valve with which the compressor apparatus is associated has been con-

ditioned to cut out of operation the low pressure top 65 of the governor device, while communication is established between the main reservoir and the pipe 78 adjacent the high pressure top 66 for rendering the valve assembly therein effective to govern operation of the compressor. With the pressure of air in the chamber 71, which pressure corresponds to that in the main reservoir, at less than the value required, the metering spring 80 consequently maintains the valve element 75 in seated position. Since the piston chamber 63 is normally connected to the atmosphere through a restricted port, not shown, only the weight of the piston 61 and associated elements oppose movement of the valve chamber 58 to its uppermost position, where it is accordingly held under the force exerted by the flow of steam entering the compressor by way of the inlet passage 18, atomizing chamber 35 and passageway 34.

The compressor apparatus is thereby operated to supply air under pressure to the receiving reservoir 97, and at the same time the automatic lubricating mechanism 25 is driven with the compressor to supply lubricant under pressure to the conduit 26, as explained in my copending patent application, *supra*.

The automatic lubricator device is operative continuously during operation of the compressor, but effects supply of lubricant under pressure to the conduit 26 at intervals, the frequency of which is determined by the speed at which the compressor is operated. Upon each pulsation or increase in the pressure of lubricant thus supplied through the conduit 26 leading to the atomizer 21 shown in Fig. 4, a quantity of lubricant is forced past the valve element 93 and is injected into the atomizing chamber 35 by way of the passage 91 and restricted orifice 91a. The fine stream of lubricant thus introduced into the atomizing chamber is at once broken into small particles or atomized by the action of the inflowing steam, which then carries the finely divided lubricant into contact not only with elements of the governor mechanism 20 but also to the reversing valve and steam valve mechanisms located in the compressor head 15.

After operation of the compressor apparatus has increased the pressure of air in the reservoir associated therewith to the value determined by the adjustment of the high pressure top 66, the corresponding fluid pressure in chamber 71 acts against the diaphragm 77 in opposition to the force of the spring 80 for permitting the unseating of the valve element 75 by spring 79. Compressed air is then admitted from the chamber 71 to chamber 63 and forces downwardly the piston 61 until the valve member 58 is brought into engagement with the seat bushing 39, thus cutting off further supply of steam to the compressor. The supply of lubricant by way of the conduit 26 is likewise stopped at this time, since the automatic lubricating mechanism 25 is pneumatically linked with and operative by the compressor.

It will be understood that the equipment illustrated in the drawings is readily adaptable to somewhat different operating conditions. For example, two compressor equipments may be provided on a locomotive and controlled from a single governor mechanism such as the mechanism 20. In this case the second compressor would preferably be provided with a steam cut-off valve controlled by compressed air which may be supplied from the chamber 63 of the illustrated equipment by way of a suitable conduit inserted

in the aperture normally closed by the plug 100, shown in Fig. 4 of the drawings. Under certain conditions it may also be desired to provide a suitable opening in the head 15 to enable connection of the atomizing chamber 35 in the compressor head directly to a steam supply pipe, rather than to the steam inlet passage 18 as shown in the drawings.

From the foregoing description of the preferred embodiment of the invention, it will be evident that the improved compressor head and governor assembly may be employed in a new or rebuilt air compressor equipment for reducing pipe installation and maintenance costs, to reduce the amount of space required for the equipment when mounted on a locomotive and to promote efficiency in the operation of the associated elements in the compressor head.

Having now described my invention, what I claim as new and desire to secure by Letters Patent, is:

1. A combination head and governor assembly for a steam driven air compressor comprising a compressor head having an elevated controlling valve portion and a steam inlet passage, steam cut-off valve means interposed in said passage, and a governor device mounted on said head for operating said cut-off valve means, said governor device having a casing structure conformed to fit about said elevated control valve portion and substantially within the outside clearance dimensions of the compressor.

2. A combination head and governor assembly for a steam driven air compressor of the vertical cross-compound type comprising a compressor head having an elevated controlling valve portion and a steam inlet passage, steam cut-off valve means interposed in said passage, and a governor device mounted on said head for operating said

cut-off valve means, said governor device including a substantially vertical body portion conformed to fit about said elevated control valve portion and a pair of horizontally disposed pilot valve portions extending from the body portion within the outside clearance of said air compressor.

3. In a steam cylinder head assembly for a cross-compound air compressor, the combination of a cast body portion having a steam inlet chamber and a steam supply passage for conducting steam to operating parts of the compressor, said body also having a partition carrying a valve seat interposed between said chamber and said passage, a lubricant atomizer device mounted in said body and operable to inject lubricant into said inlet passage adjacent said valve seat, and compressor governor means mounted on said body and including a valve movable into and out of engagement with said valve seat for controlling admission of both steam and lubricant to said passage.

4. In a steam driven cross-compound air compressor for a locomotive, a combination cylinder head and compressor governor assemblage comprising a head section having an elevated control portion and a cored ledge portion having an apertured bolting face, said ledge portion also having an interior partition carrying a valve seat and defining a steam inlet chamber and a steam supply passage for conducting steam into said control portion, a governor device mounted on said bolting face of the ledge portion, said governor device being conformed to fit about said elevated control portion within the outside clearance dimensions of the compressor, and valve means operatively mounted in said governor device for cooperation with said valve seat within said ledge portion.

ELLIS E. HEWITT.
